(57) **CLAIM**

The ornamental design for a multi-functional sink as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of a first embodiment of the multi-functional sink;

FIG. 2 is a top plan view thereof;

FIG. 3 is a bottom perspective view thereof;

FIG. 4 is a bottom plan view thereof;

FIG. 5 is a back plan view thereof;

FIG. 6 is a front plan view thereof;

FIG. 7 is a left side plan view thereof;

FIG. 8 is a right side plan view thereof;

FIG. 9 is a top perspective view of a second embodiment of the multi-functional sink;

FIG. 10 is a top plan view thereof;

FIG. 11 is a bottom perspective view thereof;

FIG. 12 is a bottom plan view thereof;

FIG. 13 is a front plan view thereof;

FIG. 14 is a back plan view thereof;

FIG. 15 is a left side plan view thereof; and,

FIG. 16 is a right side plan view thereof.
